US00D599382S

(12) **United States Design Patent**
Tsai

(10) **Patent No.:** US D599,382 S
(45) **Date of Patent:** ** Sep. 1, 2009

(54) **RIVETING MACHINE**

(76) Inventor: **Chia-Lin Tsai**, No. 53, Lane 134,
Dongan Road, Tainan City (TW) 70160

(**) Term: **14 Years**

(21) Appl. No.: **29/314,555**

(22) Filed: **Apr. 8, 2009**

(51) **LOC (9) Cl.** 15-09

(52) **U.S. Cl.** D15/128

(58) **Field of Classification Search** D15/122,
D15/128; 29/34 B, 243.53, 243.54, 407.09,
29/524.1, 525.06; 72/455; 227/51, 61, 62

See application file for complete search history.

(57) **CLAIM**

The ornamental design for a riveting machine, as shown and described.

DESCRIPTION

FIG. 1 is a perspective view of a riveting machine showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict unclaimed environmental subject matter.
